CLAIM

The ornamental design for an air filter element having attached cover member, as shown and described.

DESCRIPTION

FIG. 1 is a perspective view of a first embodiment of an air filter element having attached cover member;

FIG. 2 is a perspective view from an end opposite of that depicted in FIG. 1 of the air filter element having attached cover member; the air filter element having a swirl design on a closed end cap;

FIG. 3 is a right side elevational view of the air filter element having attached cover member depicted in FIG. 1;

FIG. 4 is a left side elevational view of the air filter element having attached cover member depicted in FIG. 1;

FIG. 5 is a top plan view of the air filter element having attached cover member depicted in FIG. 1;

FIG. 6 is a bottom plan view of the air filter element having attached cover member depicted in FIG. 1;

FIG. 7 is a front end elevational view of the air filter element having attached cover member depicted in FIG. 1;

FIG. 8 is a rear end elevational view of the air filter element having attached cover member depicted in FIG. 1; and,

FIG. 9 is a left side elevational view of an alternate embodiment of the air filter element having attached cover member; the perspective views being the same as depicted in FIG. 1 and FIG. 2; a right side elevational view being the same as depicted in FIG. 3; a top view being the same as depicted in FIG. 5; a bottom plan view being the same as depicted in FIG. 6; a front end elevational view being the same as depicted in FIG. 7; and a rear end elevational view being the same as depicted in FIG. 8.
